UNITED STATES PATENT OFFICE.

JOHN EDWARD ENGLAND, OF SPRINGFIELD, MISSOURI.

MILKING STOOL.

Application filed June 17, 1925. Serial No. 37,831.

This invention relates to certain new and useful improvements in milking stools embodying means for supporting the milk pail during the milking operation.

5 The primary object of the present invention is to provide a stool of the above kind which is extremely simple and durable in construction and by means of which the milking operation may be facilitated without danger of the milk pail tilting over 10 under ordinary conditions.

Another object is to provide the stool proper with simple and effective means for supporting and retaining the pail in proper 15 position in front of the occupant of the stool when in use.

Other objects will appear as the nature 20 of the invention is better understood, and the same consists in the novel form, combination and arrangement of parts hereinafter more fully described, shown in the accompanying drawing and claimed.

In the drawing, wherein like reference 25 characters indicate corresponding parts throughout the several views,

Figure 1 is a side elevational view of a milking stool constructed in accordance with the present invention and supporting a pail which is shown partly broken away,

30 Figure 2 is a top plan view of the stool, Figure 3 is a fragmentary longitudinal section thereof, and

Figure 4 is a perspective view of the pail retaining hook and rod.

35 Referring more in detail to the drawing, the present invention embodies a seat board 5 supported in a horizontal position at the required elevation by means of a pair of runners 6 arranged longitudinally of and at 40 the sides of the seat board.

The runners may be formed of strips of metal or strap iron with their ends respectively secured to the ends of transverse cleats 7 secured to the underside of the seat board 5 at the rear end and adjacent the forward end of the latter, the horizontal ground engaging portions of the runners projecting forwardly beyond the forward end of the seat board for a purpose which will presently become apparent.

45 A horizontal support is secured to and projects forwardly from the forward vertical end portions of the runners below the seat board 5, and this support preferably 50 embodies a rigid U-shaped strap 8 which has its ends attached to the runners. The forward end of the latter, and means to re-

forward end of the seat board is recessed as at 9 so as to partially embrace the milk pail 10 when placed upon the support 8, and means is provided to releasably retain 60 the pail in place upon said support. As shown, this means embodies a rod 11 vertically slidably through the seat board 5 at the forward end of and intermediate the sides of the latter, the upper end of said rod 65 being formed to provide a hook 12 engageable over the upper edge of the pail. The rod 11 is yieldingly urged downwardly by means of a helical spring 13 which surrounds the same between the seat board and 70 a nut 14 adjustably threaded on the lower end of the said rod. By means of the nut, the tension of the spring may be properly adjusted for causing the hook 12 to engage 75 the pail firmly so that the latter may not be accidentally displaced.

It will be seen that the forward ends of the runners project forwardly at opposite sides of the pail disposed on the support 8 so that tilting of the stool is prevented under 80 ordinary conditions, and as the pail holding means including the hook 12 retains the pail substantially stationary with respect to the stool proper, tilting of the pail and consequent loss of its contents is rendered un- 85 likely.

The rod 11 is formed with a loop 15 adjacent hook 12 and above the seat board, and this loop is adapted to be engaged by the finger for facilitating manual raising 90 of the rod 11 if desired to release the hook 12 from the pail. Also, the loop 15 engages the seat board to limit downwardly sliding movement of the rod 11.

In use, the stool is so placed as to position 95 the pail properly for receiving the milk during the milking operation, the user being seated upon and straddling the seat board while facing toward the pail.

From the foregoing description it is 100 believed that the construction and operation as well as the advantages of the present invention will be readily understood and appreciated by those skilled in the art.

Minor changes may be made without departing 105 from the spirit and scope of the invention as claimed.

What I claim as new is:

1. A milking stool including a seat board, 110 supporting means for said seat board, a pail support mounted below the seat board at the

tain a pail on said support, said pail retaining means embodying a rod slidable vertically through the seat board and having a hooked upper end adapted to engage over 5 the upper edge of the pail, and a spring encircling the rod beneath the seat board for forcing the rod downwardly.

2. A milking stool including a seat board, supporting runners for the seat board arranged longitudinally of and at the sides 10 of the latter, said runners comprising strips of metal having upright end portions secured at their upper ends to the under side of the

seat board at the ends of the latter, said runners having return-bent intermediate 15 portions providing horizontal ground engaging members which project forwardly beyond the forward end of the seat board and beyond the forward upright end portions of the runners, and a pail support 20 mounted on the forward upright end portions of the runners below the seat board and at the forward end of the latter.

In testimony whereof, I affix my signature.

JOHN EDWARD ENGLAND.
